UNITED STATES PATENT OFFICE.

GEORGE ORENSHAW, OF WEST PHILADELPHIA, PENNSYLVANIA.

DESIGN FOR A NEWSPAPER-HOLDER.

SPECIFICATION forming part of Design No. 35,585, dated January 14, 1902.

Application filed November 30, 1901. Serial No. 84,272. Term of patent 7 years.

To all whom it may concern:

Be it known that I, GEORGE ORENSHAW, a citizen of the United States, residing at West Philadelphia, in the county of Philadelphia and State of Pennsylvania, have invented and produced a new and original Design for a Newspaper-Holder, of which the following is a specification.

This invention relates to a new and original design for a newspaper-holder, and the essential feature resides in the formation of a downwardly-diverged body of hollow form, which is open at the bottom.

In the drawings, Figure 1 is a perspective view of a newspaper-holder embodying the features of the design. Fig. 2 is a transverse vertical section of the same. Fig. 3 is a top plan view thereof.

The design is characterized by a down-

wardly-diverged hollow body 1, with a lower opening 2, and having an upward projection 3, with an opening 4 therein. The rear portion of the body 1, near the bottom, also has an opening 5 therethrough. The upper portion of the body 1 merges off into the projection 3, as at 6.

Having thus described the invention, what is claimed as new is—

The design for a newspaper-holder, as herein shown and described.

In testimony that I claim the foregoing as my own I have hereto affixed my signature in the presence of two witnesses.

GEORGE ORENSHAW.

Witnesses:

JOSEPH P. WILKINSON,
GRACE WILKINSON.
